[57] CLAIM

The ornamental design for a combined surgical tube and cable securing tape, as shown and described.

DESCRIPTION

FIG. 1 is a perspective view of a combined surgical tube and cable securing tape showing my new design;

FIG. 2 is a top view thereof;

FIG. 3 is a left side view thereof, the right side view being a mirror image thereof;

FIG. 4 is a first end view thereof, the second end view being a mirror image thereof;

FIG. 5 is a bottom view thereof; and,

FIG. 6 is a perspective view thereof shown in use, the broken line showing of the tube and surface is for illustrative purposes only and forms no part of the claimed design.
